(57) **CLAIM**

The ornamental design for an earphone holder, as shown and described.

DESCRIPTION

FIG. 1 is a perspective view showing my new design;

FIG. 2 is a front view thereof;

FIG. 3 is a back view thereof;

FIG. 4 is left view thereof;

FIG. 5 is right view thereof;

FIG. 6 is top view thereof;

FIG. 7 is a bottom view thereof;

FIG. 8 is a first perspective view of the device in its environmental context thereof; and,

FIG. 9 is a second perspective view of the device in its environmental context thereof.

The portions indicated with a broken line are for illustrative purposes only, and form no part of the claimed design.
